INFLATABLE BALL

Archibald J. Turner, Chicago, Ill., assignor to
 Wilson-Western Sporting Goods Co., Chicago,
 Ill., a corporation of Delaware

Application January 4, 1930, Serial No. 418,464

17 Claims. (Cl. 273—65)

My invention relates to inflatable balls such as basket balls, foot balls, and the like, comprising an outer casing, usually of leather, and an inner bladder, usually of rubber. My present invention is preferably embodied in casing constructions having a bladder inflation aperture spaced away from the customary laced bladder insertion slit or opening.

The object of my present invention is to improve the anchorage whereby the bladder with its inflation valve is held against the inside of the cover in association with the inflation aperture.

Among the outstanding advantages of my invention are the provision of: a quick detachable anchorage for the purpose described; an anchorage which does not require the time nor the awkwardness of turning the bladder within the cover as in the usual screw type anchorage; a quick detachable anchorage which will still permit of relative rotation of the bladder and cover prior to complete inflation so that the bladder may adjust itself without straining the bladder at the region of the valve; an anchorage requiring a minimum dimension in a direction radially of the ball so that the bladder, even at the region of the valve stem may lie close to the cover; and an anchorage which, while being quickly detachable, will hold the valve of the bladder in position relative to the casing and against any ordinary lateral or inward movement occasioned by the attachment or detachment of the usual air pump. Another feature of my invention is the simplification of the stitching necessary to the assembly of the anchorage members.

These together with other objects, features and advantages of my invention are set forth in the following description of a specific embodiment thereof, as illustrated in the attached drawings, wherein

Fig. 1 is a perspective view of a basket ball embodying my invention, a portion of the cover being broken away to reveal the anchorage;

Fig. 2 is a plan view of the inside of the ball showing the cover-carried anchorage member;

Fig. 3 is a perspective detail of the cover-carried anchorage member illustrating how the bladder-carried button member is inserted there-

in;

Fig. 4 is an enlarged transverse section taken on the line 4—4 of Fig. 2 but showing the bladder-carried anchorage member positioned in the cover-carried anchorage member;

Fig. 5 is an exploded perspective of the sev-

eral pieces of the cover-carried anchorage member of Figs. 2 and 3; and

Fig. 6 is a section somewhat similar to Fig. 4, but showing only the bladder-carried members, and illustrating a modification wherein the head of the stem is formed by a nut threaded on to the end of the stem.

The basket ball shown in Fig. 1 has a leather cover 10 with the usual laced opening or slit 11 through which the rubber bladder 12 is inserted.

The bladder 12 carries an inflation check valve 13, preferably of the Schrader type, housed in a valve stem 14, the major portion of which extends inwardly through the wall of the bladder. A minor length of the valve stem extends outwardly beyond the wall of the bladder and carries an enlarged disc-shaped button 15. The button is spaced outwardly a short distance from the wall of the bladder. The bore of the valve stem, which also passes through the button portion 15, is preferably internally threaded to receive the coupling of an air pump, and the bore of the stem constitutes the air passage for the inflation of the bladder.

Access to the valve stem from the exterior of the cover is had through a small inflation aperture 16 through the casing, the aperture being preferably about the same diameter as the valve stem so as to accommodate the coupling member of the usual air pump. This inflation aperture is preferably spaced from the laced bladder insertion opening 11 and, for the purpose of balance, is preferably spaced about 180 degrees away from the opening 11.

The cover-carried anchorage member which cooperates with the valve stem button 15 to hold the valve stem in proper relation to the inflation aperture 16 comprises a set of three superposed disc-like layers:

The first of these, 17, is a cushioning or buffer layer laid directly against the inside of the cover (or, if the cover has a lining 10', then directly against the inside of the lining). The cushioning member has a central aperture 17' registering with the aperture 16 of the cover, and preferably of substantially the same diameter.

The second disc, 18, is substantially the same thickness as the button 15 of the valve stem and has a central aperture but slightly larger than the diameter of the button.

The third disc, 19, is of a thickness but slightly less than the distance by which the button 15 is spaced from the wall of the bladder, and it has a central aperture but slightly larger than

the neck of the valve stem adjacent the button 15. This third disc 19 has a radial slot 20 extending from the central aperture 19' to the periphery, the width of the slot being substantially the same as the diameter of the neck of the stem, and preferably being outwardly flared near the periphery of the disc to facilitate the entry of the neck of the valve stem there-along. The side of the periphery of the innermost disc 19 adjacent the mouth of the slot 20 is preferably truncated or cut away at 21. The three superposed discs 17, 18 and 19 are secured together and to the inner side of the wall 10 by a circular stitching 22 passing through the cover 15 and the three discs adjacent the periphery of the latter. Because of the cutting away at 21 of the periphery of the third disc 19, the edge of the disc adjacent the mouth of the slot 20 falls radially within the line of stitching and forms a pair of opposed flaps which can be raised to a limited extent to permit the passage of the button 15 between the flaps and the face of the second disc 18. To prevent undue strain on the bladder wall by an abrupt step-down, the discs 25 are preferably of progressively increasing diameter and their edges are preferably tapered off as indicated at 23.

However, the periphery of the third disc 19, where it is truncated at 21, is preferably trimmed so that its edge tapers in opposite direction as indicated at 21' to facilitate the insertion of the button 15 below the opposed flaps forming the slot 20.

To anchor the bladder to the inside of the cover with my improved anchorage means, the bladder is of course wholly or at least partially deflated and inserted into the cover through the unlaced opening 11. The bladder is held in the hand with the fingers grasping it at the region 40 of the valve stem 14, and the button 15 is brought into position, as shown in Fig. 3, in alignment with the slot 20 and with the rounded periphery of the button engaging the reversed tapered edge 21' of the third disc 19. The button is moved laterally toward the central aperture 19' with the button itself moving between the layer 19 and the layer 18 and the neck of the valve stem passing along the slot 20 until it reaches the aperture 19', when the button drops down into the central aperture 18' of the second disc 18. When this is done the flaps of the disc 19 forming the margin of the slot 20 again resume their normal position in contact with the face of the second disc 18, and the button is snugly locked 55 in the cavity formed by the aperture 18'.

This attachment is very quickly effected, it not being necessary to turn the bladder. Should the bladder—especially in the instance of a football—not be axially aligned with the cover, my anchorage permits of the bladder and the bladder stem turning in the cover-carried anchorage member properly to align the bladder. After the bladder insertion opening 11 in the cover is laced up, the coupling of an air pump may be inserted from the exterior of the cover through the inflation aperture 16 and threaded into the bore of the valve stem 14, and the bladder inflated. The disc 19, during such attachment of the pump, prevents the valve stem being pushed inwardly out of reach of the pump coupling or out of registry with the opening 16 in the cover. The discs 18 and 19 together prevent lateral movement of the valve stem out of registry with the opening 16 in the cover. After the bladder 75 has been fully inflated, its internal pressure

holds the anchorage against any possibility of accidental detachment.

Detachment of the bladder, after it has been deflated for removal through the laced opening 11, is effected by an obvious reversal of the 80 method of attachment.

The function of the first disc 17, which lies immediately against the cover or its lining, is to protect the cover against direct chafing by the metal button 15 and also to provide additional resilience between the exterior of the cover and the metal valve to protect the valve and to provide sufficient resilience so as not to give any eccentricity to the rebound in the event of impact in the vicinity of the inflation aperture 16.

It will be noted that in addition to simplifying the operation of attachment and detachment with my improved anchorage means, and the elimination of the necessity for turning the bladder within the cover to effect the attachment, I have provided an anchorage means which is very simple and which includes no interengaging parts which are subject to wear or breakage as in the instance of threaded couplings or snap type couplings.

If desired, my invention may be adapted to utilize the present commercial design of bladders made for use with the screw type anchorage, by more or less permanently threading upon the protruding externally threaded valve stem 105 14 (see Fig. 6) an internally threaded bushing 25 comprising a neck portion 26 and a button portion 27 corresponding to the button 15 of Fig. 4.

I contemplate also that if desired the equivalent of the three layers 17, 18 and 19 could be produced by molding a piece of rubber, for example, to their conformation.

The advantage of arranging my anchoring means with the button member carried by the 115 bladder and the slot member carried by the cover is that the smaller of the two members may be carried by the bladder and that the metal next to the cover is minimized, as compared to a construction where the arrangement 120 would be reversed, that is, where the button member would be carried by the cover and the slot member by the bladder.

I contemplate that other changes also may be made over the specific embodiments herein disclosed without departing from the spirit or scope of my invention.

I claim:

- An inflatable ball comprising a cover having a closable bladder insertion opening and an 130 inflation aperture through the cover, a set of three superimposed discs secured to the inside of the cover by annular stitching through the cover and the superimposed discs, the discs having central openings in substantial registry with 135 the bladder insertion opening through the cover, the central opening of the intermediate disc being of greater diameter than those of the first and third discs, whereby a socket is formed, a slot extending from the central opening in the 140 third disc to its periphery, the disc being cut away along its periphery in the region of the mouth of the slot to a radius less than that of the stitching whereby the edges of the slot are yieldable to raise away from the intermediate 145 layer, and a valve stem carried by the bladder and extending through the wall thereof, and forming an inflation passage for the bladder, an inflation check valve carried by the bladder and in communication with the passage, the outer 150

- end of the stem protruding beyond the wall of the bladder and having an enlarged button-like head spaced away from the wall of the bladder, the neck formed by the protruding stem being adapted to pass through the slot in the third disc for lateral insertion of the head into the socket. 5
2. In combination with the cover of an inflatable ball having an inflation aperture there-through, of a bladder anchorage member comprising a pair of superposed disc members secured to the inside of the cover, a far disc member having a key-hole shaped opening extending outwardly to its periphery, and a near disc member having a central opening of greater diameter than the head of the key-hole slot, and a button-like member carried by the bladder at a spaced distance outwardly from the wall thereof, for quick detachable reception by said 10 anchorage member.
3. An inflatable ball comprising a cover, a separate removable bladder therefor, an inflation aperture through the cover, an inflation valve carried by the bladder, and a pair of co-operating anchorage members, one carried by the bladder and the other by the cover, the bladder-carried anchorage member comprising a hollow stem communicating with the valve and extending outwardly beyond the wall of the bladder 15 and carrying a button-like head, and a cover-carried anchorage member comprising a near disc secured to the cover and having a central aperture in registry with the inflation aperture of the cover but of greater diameter than the 20 inflation aperture, which central aperture forms a socket adapted to receive said head, and a far disc overlying the near disc and having a central aperture smaller than that of the near disc for confining the head therein against 25 movement away from the cover, said far disc having an entrance slot whereby the head may be moved laterally into said socket.
4. An inflatable ball comprising a cover having an inflation aperture there-through and a 30 separate removable bladder having an inflation valve and quick-detachable means for anchoring the bladder on the inside of the cover with the inflation valve in association with the inflation aperture, said means comprising members carried on the inside of the cover and on 35 the bladder respectively, one of said members comprising a head or button portion, and the other an open, unobstructed slot for laterally receiving and positioning the head, said second member being attached to the cover by fastening means which terminates short of the slot 40 to permit reception of said head or button.
5. An inflatable ball comprising a cover having an inflation aperture there-through and a 45 separate removable bladder having an inflation valve and quick-detachable means for anchoring the bladder on the inside of the cover with the inflation valve in association with the inflation aperture, said means comprising members carried on the inside of the cover and on 50 the bladder respectively, the bladder-carried member comprising a head or button portion, and the cover-carried member comprising an open, unobstructed slot portion for laterally receiving and positioning the head, said second member being attached to the cover by fastening 55 means which terminates short of the slot to permit reception of said head or button.
6. An inflation ball comprising a cover having 60 an inflation aperture there-through, a separate removable inflatable bladder carrying an inflation conduit, a circular anchoring socket member stitched to the inside of the cover in registry with the inflation aperture and comprising a near disc having a central aperture and a far disc superimposed thereon, the discs being secured together and to the cover by a circular stitching, the far disc being cut away adjacent its periphery at one side within the circular line of stitching and having a slot extending inwardly therefrom to the center, and a head or button member carried by the inflation conduit of the bladder for cooperation with the anchoring member by lateral insertion along said slot and securement in the socket formed by the 65 central opening of the near disc. 80
7. An inflatable ball comprising a cover having an inflation aperture therefor, a separate removable bladder having a protruding inflation valve stem with an annular flange spaced away from the wall of the bladder forming a head, and an anchorage member secured on the inside of the cover for holding the bladder stem in association with the inflation aperture, said anchorage member comprising a patch member having a central aperture larger than, and in registry with, the inflation aperture, and a retaining patch member secured to the cover and over-lying the first patch member, the retaining patch member having a key hole shaped slot 70 extending to its periphery, the retaining patch at the margins of the slot being outwardly yieldable to permit the insertion of the head thereunder for lateral movement of the head along said slot and into the socket formed by the 75 central opening of the first patch. 90
8. An inflatable ball comprising a cover having an inflation aperture there-through, a separate removable bladder having an inflation stem carrying a protruding head, means for detachably anchoring the bladder on the inside of the cover and with the inflation stem in association with the inflation aperture, comprising a socket carried on the inside of the cover for the reception of the head, a retaining member for 80 holding the head in the socket against inward displacement, said means being yieldable to permit the removal of the head from the socket by inward and then lateral movement, said yielding retaining member, when the bladder is in 85 place and inflated, being yieldable only against the internal pressure of the bladder. 100
9. An inflatable ball comprising a bladder insertion opening and an inflation aperture spaced therefrom, a separate removable bladder having an inflation stem, and means for detachably anchoring the bladder to the inside of the cover with the inflation stem in association with the inflation aperture, comprising a patch member sewn to the inside of the cover on a plurality of sides of the aperture, annular filler means spacing the patch member from the cover at the region of the aperture and together with the inside of the cover and the patch member forming a socket in association with the inflation aperture, the inflation stem of the bladder protruding outwardly as a neck from the wall of the bladder and having an enlarged button-like head at a spaced distance from the wall, a hole in the patch member for receiving the neck of the stem when its head is received in the socket, and slit means leading outwardly from the hole to permit the removal of the head to detach the bladder from its anchorage, without 95 110
10. An inflation ball comprising a cover having an inflation aperture there-through, a separate removable bladder having an inflation stem carrying a protruding head, means for detachably anchoring the bladder on the inside of the cover and with the inflation stem in association with the inflation aperture, comprising a socket carried on the inside of the cover for the reception of the head, a retaining member for 105 holding the head in the socket against inward displacement, said means being yieldable to permit the removal of the head from the socket by inward and then lateral movement, said yielding retaining member, when the bladder is in 110 place and inflated, being yieldable only against the internal pressure of the bladder. 115
11. An inflation ball comprising a bladder insertion opening and an inflation aperture spaced therefrom, a separate removable bladder having an inflation stem, and means for detachably anchoring the bladder to the inside of the cover with the inflation stem in association with the inflation aperture, comprising a patch member sewn to the inside of the cover on a plurality of sides of the aperture, annular filler means spacing the patch member from the cover at the region of the aperture and together with the inside of the cover and the patch member forming a socket in association with the inflation aperture, the inflation stem of the bladder protruding outwardly as a neck from the wall of the bladder and having an enlarged button-like head at a spaced distance from the wall, a hole in the patch member for receiving the neck of the stem when its head is received in the socket, and slit means leading outwardly from the hole to permit the removal of the head to detach the bladder from its anchorage, without 120 125
12. An inflation ball comprising a bladder insertion opening and an inflation aperture spaced therefrom, a separate removable bladder having an inflation stem, and means for detachably anchoring the bladder to the inside of the cover with the inflation stem in association with the inflation aperture, comprising a patch member sewn to the inside of the cover on a plurality of sides of the aperture, annular filler means spacing the patch member from the cover at the region of the aperture and together with the inside of the cover and the patch member forming a socket in association with the inflation aperture, the inflation stem of the bladder protruding outwardly as a neck from the wall of the bladder and having an enlarged button-like head at a spaced distance from the wall, a hole in the patch member for receiving the neck of the stem when its head is received in the socket, and slit means leading outwardly from the hole to permit the removal of the head to detach the bladder from its anchorage, without 130 135
13. An inflation ball comprising a bladder insertion opening and an inflation aperture spaced therefrom, a separate removable bladder having an inflation stem, and means for detachably anchoring the bladder to the inside of the cover with the inflation stem in association with the inflation aperture, comprising a patch member sewn to the inside of the cover on a plurality of sides of the aperture, annular filler means spacing the patch member from the cover at the region of the aperture and together with the inside of the cover and the patch member forming a socket in association with the inflation aperture, the inflation stem of the bladder protruding outwardly as a neck from the wall of the bladder and having an enlarged button-like head at a spaced distance from the wall, a hole in the patch member for receiving the neck of the stem when its head is received in the socket, and slit means leading outwardly from the hole to permit the removal of the head to detach the bladder from its anchorage, without 140 145
14. An inflation ball comprising a bladder insertion opening and an inflation aperture spaced therefrom, a separate removable bladder having an inflation stem, and means for detachably anchoring the bladder to the inside of the cover with the inflation stem in association with the inflation aperture, comprising a patch member sewn to the inside of the cover on a plurality of sides of the aperture, annular filler means spacing the patch member from the cover at the region of the aperture and together with the inside of the cover and the patch member forming a socket in association with the inflation aperture, the inflation stem of the bladder protruding outwardly as a neck from the wall of the bladder and having an enlarged button-like head at a spaced distance from the wall, a hole in the patch member for receiving the neck of the stem when its head is received in the socket, and slit means leading outwardly from the hole to permit the removal of the head to detach the bladder from its anchorage, without 150

which slit means the head normally would not be removable from the socket.

10. An inflatable ball comprising a cover having a bladder insertion opening and an inflation aperture spaced therefrom, a separate removable bladder having an inflation stem, and means for detachably anchoring the bladder on the inside of the cover with its inflation stem in association with the inflation aperture, comprising a head on an outwardly protruding end of the inflation stem forming a reduced neck between it and the wall of the bladder, a patch member fixed on the inside of the cover at the region of the inflation aperture and defining a pre-formed socket between it and the cover for the reception of the head of the protruding stem, a hole in the patch member for the reception of the neck, and slit means in the patch member leading from the hole to the edge thereof, and means for fastening said patch member adjacent its edge to said cover, said fastening means terminating short of said slit means thereby to permit lateral insertion and withdrawal of the head from the socket.
25. 11. An inflatable ball comprising a cover having a bladder insertion opening and an inflation aperture spaced therefrom, a separate removable bladder having an inflation stem, and means for detachably anchoring the bladder on the inside of the cover with its inflation stem in association with the inflation aperture, comprising an outward neck protrusion of the inflation stem having a head a spaced distance from the wall of the bladder, a patch member secured to the inside of the cover at the region of the inflation aperture and forming a socket between the patch member and the cover for the reception of the head of the inflation stem, a hole in the patch member for the reception of the neck when the head is in the socket, and open, unobstructed slit in the patch member extending outward from the hole and terminating in a mouth for facilitating the removal of the head, the means for fastening said patch member to the cover terminating short of said mouth to permit insertion of said head into and its withdrawal from the socket between the patch member and cover.
50. 12. An inflatable ball comprising a cover having an inflation aperture, a separate removable inflatable bladder having an inflation stem, and means for detachably anchoring the bladder on the inside of the cover with the inflation stem in inflation association with the inflation aperture, comprising a nut member for detachable inter-engagement with the bladder at the region of the inflation stem, means for detachably securing the nut on the inside of the cover in inflation association with the inflation aperture, the bladder being attachable to the nut-like member while the bladder is held in its position at the inside of the cover.
55. 13. An inflatable ball comprising a cover having an inflation aperture, a separate removable inflatable bladder having an inflation stem, and means for detachably anchoring the bladder on the inside of the cover with the inflation stem in inflation association with the inflation aperture, comprising a nut member for detachable inter-engagement with the bladder at the region of the inflation stem, means for detachably securing the nut on the inside of the cover in

inflation association with the inflation aperture, the bladder being detachable from the nut-like member while the bladder is held in its position at the inside of the cover.

14. An inflatable ball comprising a cover having an inflation aperture, a separate removable inflatable bladder having an inflation stem, and means for detachably anchoring the bladder on the inside of the cover with the inflation stem in inflation association with the inflation aperture, comprising a nut member for detachable inter-engagement with the bladder at the region of the inflation stem, means for detachably securing the nut on the inside of the cover in inflation association with the inflation aperture, the bladder being attachable to and detachable from the nut-like member while the bladder is held in its position at the inside of the cover.

15. An inflatable ball comprising a cover having an inflation aperture, a separate removable inflatable bladder having an inflation stem and means for detachably anchoring the bladder on the inside of the cover with the inflation stem in operative association with the inflation aperture, comprising a nut member for detachable inter-engagement with the bladder at the region of the inflation stem, means for detachably securing the nut on the inside of the cover in operative association with the inflation aperture, the bladder being removably attachable and detachable from the anchorage as a unit with the nut.

16. An inflatable ball comprising a cover having an inflation aperture, a separate bladder having an inflation stem and means for detachably anchoring the bladder on the inside of the cover with the inflation stem in association with the inflation aperture comprising an outward neck forming a protrusion of the inflation stem and a head thereon spaced from the wall of the bladder, an annular filler strip on the inside of the cover surrounding the inflation aperture, a patch member covering the annular filler strip and forming together with the cover and the annular opening in the filler strip a socket for the reception of the head, a hole in the patch member for the reception of the neck of the bladder inflation stem when its head is in said socket, and a slit in the patch member extending outwardly from the hole to permit the flexure of the lips of the patch member adjacent the slit for facilitating the removal of the head of the socket.

17. An inflatable ball comprising a cover having an inflation aperture, a separate bladder having an inflation stem and means for detachably anchoring the bladder on the inside of the cover with the inflation stem in association with the inflation aperture comprising a patch member secured to the inside of the cover, a socket between the patch member and the cover, an outward neck forming a protrusion of the inflation stem and a head thereon spaced from the wall of the bladder, a hole in the patch member communicating with the socket for the reception of the neck of the bladder inflation stem when its head is in said socket, and a slit in the patch member extending outwardly from the hole to permit the flexure of the lips of the patch member adjacent the slit for facilitating the removal of the head of the socket.

ARCHIBALD J. TURNER.
